UNITED STATES PATENT OFFICE.

MELVILLE E. PETERS, GEORGE H. FATH, AND ALBERT F. MILLER, OF DENVER, COLORADO, ASSIGNORS TO THE PETERS PATENT RIGHTS COMPANY, OF DENVER, COLORADO, A CORPORATION OF COLORADO.

GAP AND SEGMENT BLANK-GUMMING CYLINDER.

1,239,816.

Specification of Letters Patent. Patented Sept. 11, 1917.

Application filed February 8, 1916. Serial No. 76,987.

To all whom it may concern:

Be it known that we, MELVILLE E. PETERS, GEORGE H. FATH, and ALBERT F. MILLER, citizens of the United States of America, 5 residing at the city and county of Denver and State of Colorado, have invented a new and useful Gap and Segment Blank-Gumming Cylinder, of which the following is a specification.

10 Our invention relates to a gap and segment blank gumming cylinder, and the objects of our invention are:

First, to provide means for coating with gum the entire surface of tight box wrapping blanks, and also of applying a coat of gum to the edges only of loose box wrapping blanks.

Second, to provide a gapped type of blank gumming cylinder that is arranged to expose the advancing edge of each blank after it has been coated with gum in order that this exposed edge may be gripped by pickers or any other suitable mechanism and peeled off of the cylinder and be carried forward 25 to further treatment.

Third, to provide a gap and segment type of blank gumming cylinder that is adapted to receive a supply of adhesive gum from any suitable source of supply, and to which 30 blanks may be fed by any suitable blank feeding mechanism, and that will gum a large number of blanks per minute, and that naturally rolls each blank upon itself and against its gummed surface and holds it 35 so that it can be unrolled from it by any suitable mechanism.

A further object of our invention is to provide a gapped and segment cylinder that will apply a coat of gum to the one side of 40 blanks or to the unprinted side of printed labels, that are made of paper, silk, leather, or any other suitable material, and that will leave them in such a manner that their advancing edge may be gripped by some suitable and operative mechanism and the blank be peeled off of the gapped cylinder in the naturally curved direction in which it will curl up the instant it is removed from the gapped gumming cylinder.

50 We attain these objects by the mechanism

illustrated in the accompanying drawings, in which:

Figure 1 is a plan view of a blank gumming cylinder having a gap in its peripheral surface, a hinged segment for normally closing said gap, and means for operating said segment, together with blank feeding and transmitting means. 55

Fig. 2 is a side elevation of the parts shown in Fig. 1. 60

Fig. 3 is a longitudinal sectional view of a blank gumming cylinder adapted for gumming the entire surface of one side of a blank.

Fig. 4 is an end view of the said cylinder, 65 partly in section, showing a blank thereon, one end of which rests upon the hinged segment which forms a movable portion of the peripheral surface of the cylinder, the mechanism for rocking said segment being 70 also shown.

Fig. 5 is a similar end view, showing the segment rocked to the opposite limit of movement from that shown in Fig. 4, thereby to release and expose the end of the 75 blank which rested thereon, so that the same may be engaged by suitable blank removing grippers.

Fig. 6 is a side view of a portion of a cylinder adapted for gumming loose-wrap 80 blanks.

Fig. 7 is an end view thereof, showing the cam-operated lever, which carries the blank engaging roller which holds the blank from slipping when the segment is moved to expose one end of the blank. 85

Fig. 8 is a transverse vertical sectional view of the loose-wrap cylinder, showing the threaded holes therein for receiving clamp-holding screws by which the blank-edge-gumming strips may be secured at points upon the cylinder to suit varying sizes of blanks. 90

Fig. 9 is a plan view of a portion of the loose-wrap-gumming cylinder, showing the strip for gumming the edge of the blank opposite that which is gummed by the segment. 95

Fig. 10 is a view of a tight-wrap blank, the entire surface of which is gummed. And 100

Fig. 11 is a view of a loose-wrap blank showing the gummed surfaces.

Similar letters of reference refer to similar parts throughout the several views.

5 Referring to the drawings,—

The numeral 1 designates a blank gumming cylinder that illustrates a form of cylinder embodying our invention. We however illustrate three arrangements of 10 gap and segment cylinders. We do not however illustrate any means for feeding glue or adhesive gum to the cylinder, as any commonly used adjustable supply or flow of gum mechanism may be employed. Our combined 15 gap and segment cylinders are adapted to apply a coat of glue or adhesive gum to blank sheets of paper or silk or other material, such as are used for wrapping or covering paste board boxes and for 20 other uses. Any suitable means may also be employed for feeding the blanks to the cylinders. We preferably however feed them against the under or lower side of the gumming cylinders by a roller, which may be 25 of any suitable construction.

This cylinder is a hollow cylinder mounted on a shaft 2 that is rotatively mounted in bearings 3 in the side frames of the machine. This blank gumming cylinder 1 is 30 provided with a transverse gap or open hole 4 that extends through its peripheral surface throughout its entire length. The gap in this blank gumming cylinder is normally closed by a segment member 5 which corresponds to a segment portion of the cylinder's 35 surface, and at each revolution it is opened at a predetermined point and draws away from the advancing edge of the blank, which is fed upon the cylinder to overlap this segment for a short distance along its edge at which point the free and exposed edge of the blank is caught by a plurality of spring actuated pickers that grab it and feed it forward onto the blank tempering and dis- 40 charging mechanism, but which do not form a part of my present invention. The peripheral surface of this segment is of the same circumferential curve and radius as the periphery of the cylinder, and presents when 45 in its place in the gap a smooth unbroken peripheral portion of true cylindrical surface of this gumming cylinder, and it normally fills the gap during about the whole of each revolution of the cylinder. The edge 50 55 6 of the gap is the leading edge as the cylinder rotates, and this edge tapers from a thin edge at a slightly curved angle rearwardly into the cylinder through the thickness of the shell of the cylinder, and to the opposite side of the axial shaft of the cylinder from this tapering edge 6 we pivotally mount on a shaft 7 the segment 5 of the cylinder 1.

The segment 5 comprises a curved strip portion which is preferably of about the

same thickness as the shell of the cylinder 65 and of the same length as the gap in the cylinder. This curved portion of the segment is provided at its opposite ends with rock arm portions 8 and 9, which are provided with hubs that are mounted on and secured to the ends of the rock shaft 7 that extend through the hubs of the cylinder, which preferably with the flanges of the cylinder are arranged at a short distance inside of the ends of the cylinder in order to 70 form a recess in each end of the cylinder in which the supporting arms of the segment and its operative mechanism could be housed. The segment is mounted within the cylinder in such relative relation to the axis of the 75 cylinder that it swings up into and neatly fills the gap in its peripheral surface, and also swings inwardly into the cylinder behind the tapered edge 6 of the gap.

Our invention contemplates that the gap forming and closing segment of the blank gumming cylinder may be moved to open and close the gap by any suitable mechanism. We preferably however arrange this feature of our invention in the following 90 manner:

To the free end of one of the rock arms we secure one end of a link 10, the opposite end of which is secured to one end of a rock arm 11, which is pivotally secured by a bolt 12 to 95 a lug formed on the adjacent flange of the cylinder. The opposite end of this rock arm is provided with a roller 13 which is arranged to be engaged by a cam 14 that is secured to the adjacent side frame of the machine as the cylinder 1 rotates. This gap closing segment is held normally closed against the edge 6^a of the gap by an expansive spring 15, which is mounted on a pin 16, which is pivotally secured at one end to 100 one of the rock arms of the segment, and its free end is slidably secured to an eye bolt 17 that is secured to a lug that is formed on the adjacent flange of the cylinder. A collar 18 is formed on the pin 16 against which and 105 between which and the eye bolt the spring 15 bears with an expansive pressure that forces the segment into the gap and holds it there against the side edge 6^a of the gap until the 110 cam engages the roller of the rock arm and moves it and its link 10 to swing the segment backward and down into the cylinder behind the opposite side edge of the gap. As the cylinder rotates it is so timed relative to the feeding movement of each blank that the 115 advancing edge of the blank is moved by a feed roller 19, or by any other suitable means, as this feed roller does not form any part of my present invention, against and onto the surface of the segment and within 120 about a quarter of an inch to a half of an inch of the advancing edge 6 of the gap of the cylinder, in which position it remains 125

until the cylinder rotates a part of its full revolution. Then when the segment has arrived in operative relation to the pickers it is instantly thrown back into the cylinder 5 out of the gap by its lever and cam mechanism, which leaves the advancing edge of the blank hanging over the edge of the gap in the clear space of the gap, and this exposed and free edge of the blank is instantly 10 caught by the pickers and is peeled off by them from the gumming cylinder onto the cylinder 20, from which it is carried to further treatment.

In Figs. 3, 4 and 5 we illustrate a modification of the movable segment of this blank gumming cylinder. In this modification the segment 21 is a partial gap filling segment and is made to normally stand against the edge 22 of the gap, and the feed movement of 20 the advancing edge of the blank is so timed relatively to the rotative speed of the gumming cylinder that the advance edge of the blank will be fed onto a part of the width of the segment from the blank feeding roller 25 19, and then when the cylinder has carried the advance edge of the blank into the path 25 of the pickers, the segment is moved away from the edge 22 of the gap to the opposite edge 23 of the gap, which movement of the 30 segment leaves the advancing edge of the blank exposed in the clear space of the gap and hanging over its edge, where it is instantly caught by the pickers and peeled off from the gumming cylinder, and is fed to 35 further treatment.

The segment in this modification of the blank gumming cylinder is provided with hub portions 24 that are mounted directly on the cylinder's supporting shaft 25 around 40 which a coiled spring 26 is placed, one end of which is secured to a collar 27 on the shaft and its opposite end is secured to the adjacent arm portion of the segment. This spring is arranged to hold the segment with 45 a constant resilient pressure up against the edge 22 of the aperture in the gumming cylinder. The gap aperture in the cylinder of this modification is made enough wider than the width of the segment to allow the segment 50 to move far enough away from the edge of the blank that laps over onto its peripheral surface to allow the freed and loose edge of the blank to be engaged by the grippers 28, which will peel it off of the gumming cylinder onto the tempering and discharging 55 mechanism.

This modified form of gap gumming cylinder is preferably made with end flanges that are even with the end of its length, and 60 through one of them an oblong aperture 29 is formed, through which a stud 30 is extended from the outside of the adjacent end, and is secured to the arm of the segment at one end, the opposite end of which is piv-

otally connected to one end of a link 31, the opposite end of which is pivotally connected to one end of a rock arm 32, which is pivotally connected intermediate of its ends to the adjacent end of the cylinder, while the free end of this rock arm is provided with a roller 33 that engages a cam surface 34 that is formed on the under side of a cam 35 which is secured in the rotating path of this roller and its rock arm, and to the adjacent side frame, by any suitable 75 means. Then as the cylinder rotates when the gap registers in proper relative position to the pickers, the roller 33 engages the cam and moves the rock arm and its link and the segment against the tension of its spring 80 26 and forces the blank overlapping edge of the segment from under the blank and away from the side edge of the gap, thus leaving the edge of the blank free and in the path of the pickers, which with either segment and cylinder in use fly under resilient pressure over and under the free edge of the blank and press it and hold it firmly under a constant resilient tension against the gripper bars of the intermittently moving conveyer, 85 as will be presently described.

We preferably use the gap closing segment for some classes of work, as the segment which normally fully fills the gap prevents gum working into the interior of the cylinder, while in the open gap modification gum will work slowly into the cylinder and necessitate the taking of the cylinder out of the machine and cleaning out its inside once in a while.

The construction above described of the blank gumming cylinder, has described the construction we employ for coating or covering the entire surface of one side of a blank A with gum, glue or other adhesive, as 90 shown in Fig. 10 the gummed surface being indicated by the entire surface of the blank being shaded.

In preparing blanks to be used for covering boxes in a manner known as loose-wrapped work, the blanks, instead of being entirely covered on one side with the adhesive substance, are gummed only on a narrow margin of both of their sides and end edges, such gummed blanks being adapted to 105 extend inside of the box and are folded down on the inner surface of a box adjacent to its upper edge.

In Fig. 11 of the drawing we have illustrated a blank with the gummed edges 110 shaded on the edges necessary for loose-wrapping purposes, these gummed edges are indicated by the shading along the side and end edges only of the blank B, shown in Fig. 11, and in Figs. 6 to 9 inclusive, where 115 we have illustrated the construction of a blank gumming cylinder especially designed to gum blanks for this character of box cov-

ering work. The circumferential surface and shell of the cylinder 36 is perforated with apertures 37 which are threaded as shown, and in these perforations screw driver screws are threaded, for the purpose of adjustably retaining narrow strips 38 and 39 of any suitable material, preferably strips of metal. The strip 38 extends in the direction of the axis of the cylinder and is adjustably held in place by means of clamping dogs 40 arranged on opposite sides of it and held in place by screws 41, which are passed through slots formed in the dogs. The edges of the dogs adjacent the said strip are beveled to conform to the beveled edges of the strips. The strip 38 is adapted to apply the adhesive gum to the narrow rear end edge 42 of the blank (see Fig. 8). It is essential that this strip 38 should be adjustable in order that it may be properly arranged to conform to the requirements of blanks of different sizes.

For gumming the area 43 on the advancing edge of the blank, the outer cylindrical curved surface of the segment bar 21 is utilized, this outer extremity being radially extended beyond the normal peripheral surface of the cylinder, to and even with the gumming exterior surface of the strips 38 and 39.

In order to gum the surfaces 44 at the opposite sides of the blank the strips 39 are properly positioned, being curved circumferentially to conform to the curvature 35 of the outer face of the cylinder. These strips are also held in place by adjustable dogs 45, which are secured to the cylinder by screws which after passing loosely through slots in the dogs thread into the cylinder. These strips 39 are consequently adjustable in order that their positions may be varied to suit the size of blanks being gummed, for loose wrap work.

In order to hold the blank in its proper position upon the cylinder against accidental creeping movement while changing the position of the segment bar to free and expose the gummed advancing edge of the blank, we apply to the central portion of the cylinder along the edge of the gap that is normally engaged by the segment, a raised strip 46, which however is of less height than the gumming strips 38 and 39, as it does not receive any gum on its surface, and 50 we apply a resilient pressure to the blank when it rests on the surface of this strip that holds it against displacement when the segment moves away from the advancing edge of the blank under the influence of the 55 crank levers 31 and 32 and the cam 35. This resilient pressure is applied to the blank on the surface of the strip 46, as follows:

A rock shaft 47 is journaled in the framework of the machine as shown in Fig. 6,

and intermediate between the ends of this shaft, a crank arm 48 is made fast, the outer end of which carries a roller 49. A coiled spring 50 surrounds the shaft, having one extremity secured to the frame as shown at 51 and its opposite end connected to an adjustable collar 52, which is held in place on the rock shaft by a set screw 53. This spring acts to throw the roller 49 against the surface of the strip 46 while a rock arm and cam mechanism normally hold the roller away and above this strip and also above and out of contact with the gumming strip 38 and segment 54, so that this roller does not touch anything except the ungummed surface of the blank and the strip 46. This rock arm and cam that hold the roller away from the cylinder are arranged as follows: One extremity of the shaft 47 beyond the frame is equipped with a crank arm 55, its outer extremity carrying a roller 56 lying in the path of a cam recess 57, formed in a disk 58 that is secured on the shaft 25 of the gumming cylinder at the side of its driving gear 59.

In gumming blanks for loose wrap work, in addition to gumming the edge portions of blanks as shown and described, it materially assists in wrapping the blanks in the corners of boxes especially when some kinds and characters of paper are used for the blanks, if a small additional area of surface 60 is gummed at the four corners of the blank as shown in the view of the loose wrap blank B, shown in Fig. 11, and while we may not always care to gum these corners, yet it will sometimes be an advantage to do so, and we consequently have provided the loose wrap with the necessary strips 61 to distribute a coat of gum on the blank at these corners. These strips are similar in height to those that distribute the gum to the edge portions of the loose wrap blanks, and they are made of a size in length and width to gum as much or as little of these four corners 60 over and in addition to the regular width of the gummed marginal edge as is desired, and they are secured on the surface of the cylinder by dogs and screws the same as the other strips. A pair of these additional corner gumming strips 61 is positioned on the cylinder even with the advancing edge 62 of the gap 63, and consequently even with the edge of the segment that normally bears against the advancing edge of the gap, as the cylinder rotates, and another pair of these corner gumming strips is located in a position on the cylinder to gum the opposite end corners of the size blanks being run through the machine, and both of these sets of strips would be placed directly close up to the segment and the strip 38 so as to distribute gum wholly over the corners of the blank without

leaving an ungummed space between the strips 38 and 61. The opposite edges of the blank are preferably gummed only along their central portions, their corners being 5 preferably left blank, as shown in the view Fig. 11 of the loose wrap blank B.

When the time comes to move the surface of the segment from under the gummed edge of the blank, the cam 58 suddenly releases 10 the crank arm 55 which permits the roller 56 to drop into the recess 57 in the cam 58 and which drop or release movement of the rock arm permits the spring 50 to throw the roller 49 with resilient pressure 15 against and hold it against the blank and the surface of the ungummed strip 46, which action of the roller grips the blank to the ungummed surface of this strip 46 as it rolls over it, due to the rotative movement 20 of the gumming cylinder, which rotates in the direction of the arrow, while at the same time the segment draws away from the gummed edge of the blank faster than the cylinder rotates and thus leaves the advancing 25 edge of the blank in the gap, where it is instantly gripped by the blank gripping finger pickers of the conveyer the same as the blanks are that are gummed all over by the gumming cylinder 1, which gums the 30 whole surface of one side of blanks which are to be used for tight-wrap box covering work, while this loose-wrap blank gumming cylinder gums only the edge portions of one side of the blanks.

35 The operation of our blank gumming gapped cylinder is as follows:

As before stated, the blanks may be fed to the cylinder by any suitable mechanism. When each blank reaches the horizontal central 40 portion of the gumming cylinder, it opens its peripheral segment and exposes the advancing edge of the blank, which is instantly seized or gripped by the finger pickers, which when released by the cam fly 45 into the gap and clamp the exposed edge of the blank to the adjacent cross-bar, as they travel around the transmission cylinder at the same speed as the gumming cylinder, and the blank is transferred by them, and 50 the transmission cylinder 20, to mechanism that carries the blank to further treatment and is arranged to manipulate the pickers to release the blank wherever desired.

Our invention provides a practical blank 55 gumming cylinder that may be used in gumming machines of various types and constructions. An illustration of its application to a gumming machine may be found in our pending application Serial Number 60 30471 filed May 25th, 1915, for a new pneumatically controlled and automatically operating blank gumming and tempering machine; and while we have illustrated and described the preferred construction of our

gumming cylinders we do not wish to be 65 limited to the construction shown, as many changes might be made without departing from the spirit of our invention.

Having described our invention, what we claim as new and desire to secure by Letters 70 Patent, is:

1. A gapped cylinder, means including a segment for closing the gap, means for feeding a blank onto said cylinder to lap onto said segment, and means for moving 75 the segment from under the edge of the blank.

2. A gapped cylinder having a segment movable in said gap to receive and expose a blank, and means including a transmission 80 mechanism for gripping the exposed edges of said blanks and for conveying them to a box covering machine.

3. In a blank gumming cylinder, a gumming cylinder having a gap and an opening 85 and closing cylindrical segment fitting said gap and arranged to receive and to expose the advancing edge of each blank at predetermined points on said gumming cylinder as it rotates, means for feeding blanks to 90 said cylinder, and means for grabbing their advancing exposed edges and removing them from said gumming cylinder, in the direction in which they would naturally curl.

4. In a blank gumming cylinder, a gum distributing cylinder provided with a gap and having a segment member forming a part of the gumming face of said gapped cylinder, said segment being positioned to receive the advancing edge of the blank and movable 100 at a predetermined point in said cylinder's rotative movement to expose the gummed edge of said blank, means for feeding blanks onto said gumming cylinder and its segment, and means for operating said 105 segment to close and open said segment to receive and to expose said blank.

5. In a box-covering blank gumming cylinder, a rotating cylinder operatively connected to blank feeding, gumming, gripping, 110 transmission and conveying mechanism, and provided with a reciprocable and movable segment surface portion of said cylinder's circumference, and arranged to form a gap in the surface of said cylinder when moved 115 away therefrom, means for feeding the blanks one at a time so that the advancing edge of the blank will engage the movable segment surface portion of said cylinder at the time it is being gummed, and will be 120 exposed in the gap formed therein when the segment portion is moved out of engagement with said gaps, means including an expansive tension spring bearing directly against the back of said segment for normally holding 125 said segment in its gap in said cylinder surface, and a cam mechanism connected to said segment and arranged to instantly open

said segment against the tension of said spring and instantly release it to the segment closing expansive tension of said spring, and means for instantly gripping 5 the gummed edge of said blank in the gap of said cylinder and for removing said gummed blank from said cylinder and transmitting it to the said conveyer.

6. In blank gumming gap and segment 10 cylinders, means for revolving a blank gumming cylinder or drum at a constant speed, means for feeding a blank to said cylinder

and coating the same with gum and intermittently operative means for gripping the blank and peeling it from said cylinder. 15

In testimony whereof we affix our signatures in presence of two witnesses.
